(57) **CLAIM**

We claim the ornamental design for a genset enclosure, as shown and described.

DESCRIPTION

FIG. 1 is a front isometric view of a genset enclosure;
FIG. 2 is a front elevational view thereof;
FIG. 3 is a rear elevational view thereof;
FIG. 4 is a left elevational view thereof;
FIG. 5 is a right elevational view thereof;
FIG. 6 is a top plan view thereof; and,
FIG. 7 is a rear isometric view thereof.

The bottom of the genset enclosure in each embodiment is unornamented and forms no part of the claimed design.
The ornamental design which is claimed is shown in solid lines in the drawings. The broken lines shown represent unclaimed subject matter and form no part of the claimed design.
